(57) **CLAIM**

The ornamental design for an endosteal dental implant, as shown and described.

DESCRIPTION

FIG. 1 is a front perspective view of a endosteal dental implant showing our new design;
FIG. 2 is a front elevation thereof;
FIG. 3 is a rear elevation thereof;
FIG. 4 is a right side elevation thereof;
FIG. 5 is a left side elevation thereof;
FIG. 6 is a top plan view thereof;
FIG. 7 is bottom plan view thereof;
FIG. 8 is a cross sectional view thereof taken along line 8—8 in FIG. 6; and,

FIG. 9 is a cross sectional view thereof taken along line 9—9 in FIG. 7.

The broken lines showing the interior of the design in FIGS. 2, 5 and 8 are for illustrative purposes only and form no part of the claimed design.
